P. Unham,

No Printed Specification Attached

Water Elevator,

Patented Jan. 6, 1809.

Henry Upman. 975X
Letters Patent.

The Schedule referred to in these Letters Patent and making part of the same, containing a description in the words of the said Henry Upman, himself of his Pneumatic forcing pump.

A bellows of such form as may be found most convenient, is to be placed over the well or other depth from whence water is to be raised; from the bottom of which bellows, in a manner similar to the common operation of that instrument, the air is forced through a tube into a barrel or small reservoir of a cylindrical or any other convenient form. The said barrel being wholly immersed in the water to be raised, the water enters and fills it thro' a valve in the bottom thereof & is prevented from escaping by the closing of the valve. The air being thus forced as above stated, the water in said barrel is thereby propelled thro' an aperture in the side and contiguous to the bottom thereof into a tube which rises from thence vertically to the height required, another valve in the last mentioned tube near the bottom thereof prevent the water from returning into the barrel. By the consequent pressure of air, occasioned by the successive action & reaction of the forward bellows a constant amount of water is made to issue from the upper end of the discharging, or last mentioned tube. To effect the above described motion of the bellows any convenient power may be applied, but it is thought that a rack & pinion applying either more or less force to the top of the bellows, so as to raise it having sufficient weight in contact thereto cause it to descend with the most suitable celerity.
